UNITED STATES PATENT OFFICE.

FREDERICK EGGE, OF BRIDGEPORT, CONNECTICUT.

REGULATING-VALVE FOR GAS-BURNERS.

No. 850,569.

Specification of Letters Patent.

Patented April 16, 1907.

Application filed June 8, 1906. Serial No. 320,776.

To all whom it may concern:

Be it known that I, FREDERICK EGGE, a citizen of the United States, residing at Bridgeport, in the county of Fairfield and State of Connecticut, have invented certain new and useful Improvements in Regulating-Valves for Gas-Burners; and I do hereby declare the following to be a full, clear, and exact description of the invention, such as will enable others skilled in the art to which it appertains to make and use the same.

My invention relates to regulating-valves for gas-burners, and consists of certain parts and arrangements of parts such as will be hereinafter fully explained and then particularly pointed out in the claim which concludes this application.

The object of my invention is to automatically prevent the accidental escape of gas from the burner.

In the accompanying drawings, which form a part of this application, Figure 1 is a vertical sectional elevation illustrating my improvement with the parts in normal position; Fig. 2, a similar view showing the position of the parts with the gas-pressure on and immediately after certain mechanical appliances have been operated to allow the escape of gas through the burner, and Fig. 3 a section taken at the line 3 3 of Fig. 1.

Similar numbers of reference denote like parts in the several figures of the drawings.

1 is the base-section of the burner internally threaded at the bottom for attachment to a gas-fixture, the upper portion of this section terminating in a reduced nipple 2, which is threaded externally. 3 is a valve-seat formed in the upper portion of this nipple, and 4 a small duct leading from the interior of the section 1 into said seat. 5 is a ball-valve which by gravity normally rests within this seat so as to cut off the escape of gas.

6 is an intermediate section hollow throughout its length and having a reduced externally-threaded upper portion, to which latter the gas-burner 7 proper is screwed, while the lower portion of this section is internally threaded and screwed on the nipple 2.

50 Pivoted at 8 between ears *a a*, projecting upwardly from the top of the nipple 2, is a gravity-dog 9, which normally swings into position immediately above and against the ball-valve 5, so as to lock the latter as against any upward movement, as shown at Fig. 1, one of the lower corners of said dog being

beveled or rounded, as shown at 10, for the purposes presently to be explained.

11 is a small tube screwed within the side of the section 6; 12, a small plunger-pin extended through this tube within said section; 13, a coil-spring within this tube and around the pin, and 14 a small head secured to the outer end of the pin. This pin is horizontally disposed, and its normal position is in a direct line with the lower portion of the dog 9.

Presupposing the parts to be in the position shown at Fig. 1, the operation of my improvement is as follows: The pin is thrust inwardly against the dog, thereby swinging the latter to one side, and thus permitting the pressure of the gas to elevate the ball-valve against the lower beveled corner 10 of the dog, as shown at Fig. 2, whereby the pressure of the gas will keep the parts in this position and the gas can then readily escape up through the burner. When the pressure of gas goes down, the ball will rest upon the valve-seat, and the dog will swing into normal position above the ball, thus locking the latter in place. The provision of the small bevel 10 on one of the lower corners of this dog permits the ball to rise without getting out of contact with the dog. If this dog had a sharp corner instead of a bevel, the ball

could not rise until it could clear the dog entirely, and this would be apt to seriously interfere with the successful operation of my improvement, because the return swing of the dog would be apt to cause the latter to impinge against the ball with sufficient force to prevent the latter from dropping back into its seat; but although I consider this bevel to be necessary in instances where I am obliged to use a very light ball made of aluminium on account of a light gas-pressure, still I do not desire to be limited thereby, since in the instance of a heavy ball and a greater gas-pressure such bevel might be done away with. Also the middle section 6 and the gas-burner proper may be made in a single piece, if desired, although for the purposes of convenient assembly I prefer the construction illustrated.

While I consider the loose ball-valve as a very simple and effective construction, it will of course be obvious that the shape of the valve is immaterial, so long as said valve is capable of a free operation by gravity.

The plunger-pin which I have shown and described or some similar mechanical device is, as a rule, necessary, although a light tap

against the side of the burner so as to cause a sufficient vibration will effect the displacement of the dog, and thus allow the pressure of gas to elevate the valve.

5 Having thus described my invention, what I claim as new, and desire to secure by Letters Patent, is—

A regulating-valve for gas-burners, comprising a base-section provided with a single 10 central gas-duct, a reduced, threaded nipple at the upper end of said section, a valve-seat overlying said gas-duct and being formed below the top of said nipple, a pair of ears

projecting upwardly from said nipple and on opposite sides of said valve-seat, a ball-valve 15 on said seat, and a gravity-dog having its upper end pivotally supported from the upper portions of said ears and having its lower end engaging said ball-valve.

In testimony whereof I affix my signature 20 in presence of two witnesses.

FREDERICK EGGE.
